[57] CLAIM

The ornamental design entitled portable, totable repository for spent smoking materials, as shown and described.

DESCRIPTION

FIG. 1 is a perspective view of the portable, totable repository for spent smoking materials;

FIG. 2 is a left side elevational view thereof, the right side being a mirror image;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view of an alternate position of the closure of the cover of the repository of FIG. 1 with an interior notch and funnel shown for illustrative purposes only; alternate views of the open closure mirror those of FIGS. 2-5.
